UNITED STATES PATENT OFFICE.

GEORGE F. BROWN, OF MOORHEAD, MINNESOTA.

COMBINATION ASH-SIFTER AND GARBAGE-CAN.

1,373,297.

Specification of Letters Patent. Patented Mar. 29, 1921.

Application filed February 16, 1918. Serial No. 217,638.

To all whom it may concern:

Be it known that I, GEORGE F. BROWN, a citizen of the United States, residing at Moorhead, in the county of Clay and State 5 of Minnesota, have invented certain new and useful Improvements in Combination Ash-Sifters and Garbage-Cans; and I do hereby declare the following to be a full, clear, and exact description of the invention, 10 such as will enable others skilled in the art to which it appertains to make and use the same.

The invention embodies in a single entity an ash sifter and a garbage can of a special 15 construction which is designed for use in households in cities and towns as well as on farms. The same lid or cover fits both the ash sifter and the garbage can so that the garbage can may be used by the farmer 20 as a feed pail or bucket.

In the drawings—

Figure 1, represents a vertical section of the assembled parts.

Fig. 2, is a fragmentary view showing the 25 formation of the margin of the cover.

Fig. 3, is a fragmentary view showing the joint for uniting the sifter receptacle, and its bottom.

Fig. 4, is a view showing construction of 30 one of the feet for the garbage vessel.

A, represents a garbage vessel which is formed in any desired manner. This vessel is provided with feet, a, having reversely bent ends, a', a'', one of which engages the 35 side of the vessel, and the other of which projects from the bottom thereof. These feet are held in place by clips, a'', extending over them and soldered at their ends to the bottom of the vessel.

40 The sifter is composed of a receptacle B, having a conical bottom, b, seamed on to it at b'. Within the receptacle and sustained on the bottom thereof, is a sifter which is a circular dished piece made of metal lathing, or expanded metal, D, this sifter being

held in position by clips, d, soldered or otherwise secured to the inner wall of the receptacle, D. The bottom of the receptacle is formed of one piece of metal bent in conical form and seamed together at its 5 meeting edges, the seam being reinforced by indentations, d'.

The cover or the lid, c, is also composed of a single piece of metal bent to conical form, the meeting edges being soldered together and the margin being doubled and extended inward and crimped to form a vertical circumferential flange within the margin of the cover. The cover is adapted to fit into and upon both the garbage vessel 60 and the receptacle of the ash sifter. The cover is of course provided with a handle for its manipulation.

It will be observed that the conical formation of the bottom, of the receptacle, B, prevents the dust from the ashes falling into the vessel, A, from escaping to the atmosphere. The sifting of ashes by the device is therefore practically dustless so that it may be accomplished in the parlor, the kitchen 65 or elsewhere without the soiling of the environment. The feet are diametrically disposed, and serve as fulcra on which the device may be tilted during the shaking operation.

Having thus described my invention, what 70 I claim and desire to secure by Letters Patent is:

A combination ash sifter and garbage can, having a lower retaining vessel, a superimposed receptacle having a flange for engaging the upper margin of said vessel, a funnel shaped open bottom for said receptacle constituting a continuation of said flange, a sifter in said receptacle and a cover having 80 a flange which is adapted to sustain said cover on the upper margin of the vessel or on the upper margin of the receptacle.

In testimony whereof, I affix my signature.

GEORGE F. BROWN.
